Fred Lasker.

UNITED STATES PATENT OFFICE.

LEWIS NOLTY, OF LANCASTER, PENNSYLVANIA.

FOLDING TABLE.

1,421,541.

Specification of Letters Patent.

Patented July 4, 1922.

Application filed March 11, 1922. Serial No. 542,996.

To all whom it may concern:

Be it known that I, LEWIS NOLTY, a citizen of the United States, and resident of Lancaster, in the county of Lancaster and 5 State of Pennsylvania, have invented certain new and useful Improvements in Folding Tables, of which the following is a specification, reference being had therein to the accompanying drawing.

10 My invention is concerned with a folding table, for sewing, cards, dining, a magazine or lamp rest, or for any other purpose which requires a light, simple, but firm structure, which can be easily folded so as 15 to occupy but little space, but can be quickly unfolded and made operative for practical use.

Tables that fold are often fragile and weak and incapable of standing much abuse, and hence the chief object of the invention is to make an improved joint or connection between the legs and the table, so that the legs will strongly support the top and will have no tendency to become 25 dislocated or to prematurely fold up and cause the table to collapse. With this and other objects in view the invention may be said to consist essentially in the construction, arrangement and combination of parts, 30 substantially as will be hereinafter described and claimed.

In the accompanying drawing illustrating my invention:

Figure 1 is a horizontal bottom plan of 35 the table top, with the places for the improved joints that connect the legs with said top indicated in dotted outline.

Figure 2 is a vertical elevation partly sectioned on the line 2, 2, of Figure 1, and 40 with a leg shown in the position it occupies when the table is unfolded and the top is being supported in its horizontal position for use.

Figure 3 is a vertical sectional elevation 45 of the same on the line 3, 3, of Figure 2, the section being at right angles to the plane of the section 2, 2.

Figure 4 is a horizontal section on the line 4, 4, of Figure 2.

Figure 5 is a side elevation, partly sectioned the same as Figure 2, of the same parts as are shown in Figure 2, but showing one leg folded up under the top and securely held there in the position assumed 55 thereby when the table is shut up in readiness to be put away.

Figure 6 is a vertical section on the line 6, 6, of Figure 5.

Figure 7 is a horizontal sectional bottom plan on the line 7, 7, of Figure 6.

60

Similar characters of reference designate corresponding parts throughout the different figures of the drawing.

1 denotes the horizontal top of the table, which is usually round, square, or oblong, 65 but may be of any shape, size and character. It will usually be provided with a vertical flange or ledge, or edge piece 2, running around the four sides or edges, and of any width and thickness, said ledge assisting to 70 provide corner recesses 1^a at the four corners of the top 1, where the legs 3 are jointed to the top 1. These legs may be of any length, shape and size, but I preferably make them square in cross-section and provide portions thereof adjacent to top 1 with longitudinal slots, cross-cuts or kerfs 4 and 4^a, which are cut at an angle, usually a right angle, to each other, and cross each other at the center of the leg, said slots 75 having a moderate length from the end of the leg longitudinally into and through the same, and dividing the leg into four square sections, or pins, as shown.

In each corner 1^a is a rigid metallic member, consisting essentially of a pair of intersecting cross-plates 6 and 7, plate 6 being considerably longer than plate 7, which plates are held rigidly in the corners 1^a by

80

suitable means, and which thus provide stationary vertical fixed attachments on the table which are adapted to enter the leg slots 4 and 4^a accordingly as the legs are manipulated to cause such an engagement.

90

These plates are soldered or otherwise secured together, and they form at their juncture as it were four pockets, channels, or guides in a socket construction to receive the four cleft sections of the legs 3. Said fixed

95

members have suitable flanges or ears to enable them to be fastened to the table top 1 and the side ledge 2 thereof; thus at one point an ear 9 projecting from the intersecting plates 6 and 7 is secured by a screw

100

or other means to the top 1, see Figures 2, 5 and 7; at another point the edge of plate 6 adjacent to ledge 2 has a flange 10 which is secured by screws to the ledge 2; and then again an edge of plate 7 has a turned over section 11 that is parallel to a part of plate 6 and helps to form one of the four channels, and said section 11 has a flange 12 that is

110

secured by screws or otherwise to the ledge 2, see Figures 3, 4 and 6. The pockets or channels around the juncture of plates 6 and 7 are more or less open but may be closed 5 or not as preferred to receive the four cleft members of the leg.

- Two of the four square pins or subdivisions into which each leg is cut by kerfs 4 and 4^a are connected by a pin 5 passing 10 horizontally through the leg, see Figure 4, and said pin 5 also passes through a slot 8 in plate 6, with which it remains permanently engaged, so that in this way the leg is loosely hung on the cross member, and is 15 manually adjustable from an active to an inactive position or the reverse. The slot 8 is U-shaped, one leg thereof extending through plate 6, and thus between two of the square channels, while the other leg of 20 the U-slot extends through plate 6 between the other two channels. By manipulating the legs, they can be guided by the movement of their pin 5 in the slots, so as to transfer them from a position where the plates 6 and 25 7 enter the slots 4 and 4^a to a position at right angles thereto where the legs slots are disengaged from the plates, that is to say from the position shown in Figure 2 to that shown in Figure 5 or the reverse.
- 30 The operation will be plainly evident from my description of the construction and arrangement of the parts. In Figure 2 a leg 3 is shown in its position when the table is unfolded and the four legs support the 35 top 1 in useful position. Here the slots 4 and 4^a are engaged with the intersecting plates 6 and 7 and the four sections or pins of the quadruple leg occupy the four channels or right-angled spaces around the inter- 40 section of the plates 6 and 7, the pin 5 at this time being at the upper end of one of the legs of the U-slot 8, said pin being now horizontal. The rigid cross-plates hold the leg absolutely firm so that it cannot become dis- 45 placed. Also if the top 1 of the table is lifted I use flat springs 13, 13, secured on ledge 2 and bearing against the leg to prevent the leg from dropping away from the socket piece, see Figure 2. Each leg when 50 extended for use is caused to receive the cross plates 6 and 7 in the slots 4 and 4^a, and in so doing the leg will be slideable end- 55 wise on said plates towards the top 1 until the end of the leg comes into contact with the under side of the said top. The legs in this position will uphold the top very securely and effectively and there will be no danger that a leg will become bent under or otherwise disarranged to allow the top to fall.
- 60 Obviously a description of the action of one leg applies to all. When, moreover, the table is to be folded, the legs will be drawn away from the top 1, and disengaged from the cross-plate members, and then turned 65 through an angle of ninety degrees and

folded up under the top 1, as shown in Figure 5, where they can be temporarily held by the spring clamp 14, it being noted that in thus transferring a leg from its active to its idle position, its pin 5 will ride along 70 through one leg of the U-slot 8, through the bend of said slot, and then through the other parallel leg of the U-slot, until the leg is snugly within the grip of clamp 14. An unfolding of the legs takes place with 75 equal ease and facility.

Obviously many changes in the mechanical details may be made without exceeding the scope of the invention, and I desire all needful liberty of making such changes. 80 Especially may I modify the form and construction of the rigid cross members that depend below the top and engage the slotted ends of the legs.

Having thus described my invention, what 85 I claim as new and desire to secure by Letters Patent, is:

1. In a folding table, the combination with the top of a fixed depending cruciform member thereon consisting of intersecting 90 plates one of which has a U-slot, and a table leg slotted to engage said plates, and having a pin engaging the U-slot.

2. In a folding table, the combination with a top, of the legs, and means for joining the legs to the top consisting essentially of corner members composed of angularly-related vertical plates rigid with the top, one of said plates having a U-slot and both adapted to enter longitudinal slots in the 100 legs when the table is unfolded and to be withdrawn therefrom when the table is folded, and pins on the legs engaging the various U-slots.

3. In a folding table, the combination with 105 the top, of the legs, and means for jointing the legs to the top consisting essentially of angularly-related vertical plates rigid with the top and adapted to enter longitudinal slots in the legs when the table is unfolded 110 and to be withdrawn therefrom when the table is folded, and means for hinging the legs to said plates comprising pins carried by the legs and entering U-shaped slots in the plates.

4. In a folding table, the combination with the top, of the legs, and means for jointing the legs to the top, consisting essentially of a pair of plates whose members intersect each other at right angles, forming sockets 120 between them, and adapted to enter right-angled intersecting slots in the legs, said legs having pins entering curved slots in the plates so as to be easily slideable and foldable.

5. In a folding table, the combination with the top, of the legs, and means for jointing the legs to the top consisting essentially of angularly-related vertical plates rigid with the top and adapted to enter longitudinal 130

slots in the legs when the table is unfolded and to be withdrawn therefrom when the table is folded, one of said plates having a U-shaped slot engaged by a pin on the legs

5 to permit folding of the legs.

6. In a folding table, the combination with the top, of cross-plate members having a U-shaped slot and attached to said top, and slotted legs engaging the said members and

10 provided with a pin that travels in the U-shaped slot.

7. In a folding table, the combination with the top, of leg-holding members consisting of plates intersecting at right angles, one of said plates having a U-slot, and legs longitudinally slotted at right angles to engage the plates, and provided with a pin that functions in the U-slot. 15

In testimony whereof I hereunto affix my signature.

LEWIS NOLTY.
